UNITED STATES PATENT OFFICE.

CHARLES O. COZZENS, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

DESIGN FOR AN END PIECE FOR AN OPHTHALMIC MOUNTING.

Application filed July 19, 1928. Serial No. 27,528. Term of patent 14 years.

To all whom it may concern:

Be it known that CHARLES O. COZZENS, a citizen of the United States of America, residing at Southbridge, in the county of Worcester and State of Massachusetts, has invented a new, original, and ornamental Design for End Piece for an Ophthalmic Mounting, of which the following is a specification, reference being made to the accompanying drawings, forming a part thereof.

Fig. 1 is a front elevation of an end piece for an ophthalmic mounting showing my new

design of end piece in full lines and fragments of the lens rims and lenses in dot and dash lines;

Fig. 2 is a top plan view of Fig. 1 showing my new design of end piece in full lines and fragments of the temple, lens rims and lenses in dot and dash lines.

I claim:

The ornamental design for an end piece for an ophthalmic mounting as shown.

In testimony whereof, I affix my signature.

CHARLES O. COZZENS.
